UNITED STATES PATENT OFFICE.

JAMES S. BOGLE, OF SPRINGFIELD, OHIO.

GRAIN-DRILL.

SPECIFICATION forming part of Letters Patent No. 223,470, dated January 18, 1880.

Application filed October 23, 1879.

To all whom it may concern:

Be it known that I, JAMES S. BOGLE, of Springfield, county of Clarke, State of Ohio, have invented a new and useful Improvement 5 in Grain-Drills, of which the following is a full, clear, and exact description, reference being had to the accompanying drawings, making part of this specification, in which—

Figure 1 is a perspective view of a grain-drill with my improvements applied. Fig. 2 is a side elevation, and Fig. 3 a rear elevation, of the same. Fig. 4 represents a vertical longitudinal section through the same. Fig. 5 is a side elevation, showing the gear-cover removed, with one of the interchangeable gears also removed and shown in reversed perspective view, Fig. 11. Fig. 6 is a perspective view of a portion of the grain-box inverted, with one of the distributers attached. Fig. 7 is a similar view of the distributer-casing detached. Fig. 8 shows, in side elevation and in perspective, the bracket or hanger and quarter-box for holding the distributer-casing and adjusting rock-shaft in place. Fig. 9 is a side elevation 25 of one of the distributers. Fig. 10 is a perspective view of the inner face of one of the distributer-casing plates. Fig. 11 is a perspective view of one of the interchangeable gears. Fig. 12 is a side elevation of the gear-lever and cam-yoke; Fig. 13, a similar view of the cam and cam-plate. Fig. 14 represents a section through one end of the lifting-roller shaft. Fig. 15 is a perspective view of the pivoted funnel or cup intermediate between the distributer and the conductor and drill-tube. Fig. 35 16 represents a modification in the devices for locking the beams through which the hoes are adjusted.

Similar letters of reference denote corresponding parts wherever used.

The invention relates to a novel construction of the distributers, and to a novel means for securing them to the grain-box and for retaining the rock-shaft through which the gages are adjusted in position; also, to a novel method of changing the speed of the distributer-wheel shaft without the aid of extra gears and without change of centers or any adjustment of parts; to the means for raising the 45 hoes or teeth, whereby a backward thrust of the lifting-lever is made to rock the lifting-

roller upward and forward past its pivotal center, adapting it to suspend the hoes or teeth elevated out of the ground without the aid of a retaining catch or pawl, at the same time cutting off the feed or flow of the grain; to a novel construction of gear-lever and yoke and of the adjustable irregular cam actuating said lever, whereby the mesh of the cogs of the driving-gears can be regulated to provide 55 for inaccuracies in the construction and adjustment of other parts, while at the same time the cam is made to so fill the lever-yoke as to prevent slack or lost motion of the lever; to a novel means for suspending the tube-tops or 60 funnels from the distributer-casings, facilitating their adjustment, removal, &c.; to a novel arrangement of pivoted angle-board, which, by a slight rocking movement, is adapted to deposit the grass-seed either in front or in rear 65 of the hoes, as desired, and to the means for holding the hoes or teeth in position when arranged either in single or double rank, all as will be explained.

In the accompanying drawings, A represents 75 the frame of the machine, B B' the carrying and driving wheels, and C the grain-box, said parts being constructed and arranged in any usual or preferred way.

The wheel B' has a spur-gear, a, connected 80 with it, from which motion is imparted to the distributer-wheel shaft, as follows: D is a gear-lever and yoke, pivoted at its forward end to and turning on the axle b of wheel B' as a center, the rear end of said lever being expanded 85 in width and provided with an irregular slot, in which a cam, hereinafter described, on one end of the lifting-roller shaft works for raising and depressing said lever. The outer face of this lever D is provided with a stud-shaft, 90 upon which is mounted a transmitting gear or pinion, a', which engages with the gear a, receiving motion therefrom.

The outer end of the hub of wheel a' has a clutch-face formed upon it similar to that 95 shown on wheel a³, Fig. 11, adapting it to engage a similar clutch on the inner end of the hub or wheel a², mounted and turning on the same stud-shaft with wheel a', said wheel a² 100 engaging and driving wheel a³ on the distributer-wheel shaft. In Figs. 5 and 11 this wheel a³ is shown removed from its shaft, its posi-

tion when in use on said shaft being indicated by the dotted lines in Fig. 5.

5 The distributor-wheel shaft E has secured to its end a rounded extension, E', (see Figs. 1 and 3,) forming a journal which has its bearing in a sleeve-box, C, formed in the end standard, C', of the grain-box.

10 The outer end of journal E' has longitudinal ribs e e, giving it a clutch form, adapting it to receive and be rotated by the wheel a³, which has a corresponding clutch-face on its hub a⁴. (See Fig. 11.)

15 The clutch-faces of wheels a² and a³ are formed alike, adapting the wheels to be interposed, and being of different diameters, by simply transposing them the speed of the distributor-shaft will be changed from a slow to a faster movement, and vice versa, for adapting the machine to sow small or large grain 20 without the aid of extra gears, change of centers, or any adjustment of parts.

25 The gears a² a³ when in place are held on their respective shafts by the removable gear-cover F.

30 The gear-lever has an irregular slot, D', in its rear end, forming a yoke, and an irregular heart-shaped cam, d, on one end of the lifting-roller shaft moves in said slot for actuating the gear-lever.

35 The expanded end of the lever D moves in close proximity with the side frame-bar on its inner face, and the cam d has a cheek-plate, d', on its outer face, outside of said lever, which serves to steady the movement of the lever and prevent its lateral displacement.

40 The lifting-roller is made in crank form, composed of the transverse rod or bar G, connected to crank-arms G', which at their inner or pivoted ends are provided with sleeve-journals rocking in suitable bearings on the main frame. These sleeves are divided into two parts, g g', the part g in each case being formed upon or rigidly connected with one of the crank-arms G, and the part g' on one side being rigidly 45 connected with the cam d and upon the other side with a gear-wheel, h, hereinafter referred to, the adjacent ends of said parts g g' of the sleeve in each case having clutch or rose plates g², (see Fig. 13,) permitting their relative adjustment in the one case for varying the throw of the cam d, and thus compensating for any inaccuracies in the construction or adjustment of other parts, and in the other case for regulating or adjusting the throw of the lifting-lever. The two parts are held in each case at the desired adjustment by a through-bolt, g³.

45 The adjustable gear-wheel h on one end of the lifting-roller shaft engages with a second gear-wheel, h', mounted on a stud-shaft, i, 60 formed upon or secured to a bracket, I, attached to the frame, the wheel h' having a lever, H, rigidly connected with it for rotating it and imparting motion to the wheel h and to the lifting-roller G, connected therewith.

65 By this arrangement of gears interposed between the lever and the lifting-roller they are made to move in opposite directions, the lever

being moved backward and downward and the lifting-roller upward and forward for raising the drill-teeth, the lifting-roller in this 70 movement being adapted to be thrown forward past its pivotal center against the grain-box or other suitable stop, in which position it is sustained, holding the hoes or teeth out of the ground without the aid of a pawl or catch. 75

The same action of the lifting-lever rocks forward and downward the cam d on the opposite end of the lifting-roller shaft, and said cam, acting upon the gear-lever or yoke D, depresses the latter and throws the gear-wheel a² out of 80 mesh with the wheel a³, thus throwing the distributor-wheel shaft out of action and stopping the discharge of the grain.

A reverse movement of the lifting-lever lowers the drill-teeth into the ground and 85 throws the wheel a² into gear with wheel a³, again setting the distributor-wheel shaft in action.

90 The form and arrangement of the cam d in its yoke is such that it acts at the beginning of the throw of the lifting-roller for raising the drill-teeth and near the end of its throw in lowering the same, thus effectually preventing the waste of grain.

95 The construction of the distributor-wheel casing and the manner of attaching the same to the bottom of the grain-box is shown in the detail views, Figs. 6, 7, 8, 9, and 10. K represents the casing made in two parts, in the usual form, except in particulars which will 100 be described.

The discharge-opening is protected in front and in rear by wind-guards k, formed one upon each part of the divided casing, and projecting in parallel lines, or thereabout, on the same side of the casing as the discharge-outlet, and in front and rear thereof, forming, in connection with the casing, a spout or passageway closed in upon three sides and protecting the grain from the action of the wind in its 110 passage from the distributor to the conductor spout or tube.

115 The upper end of the casing is provided with flanges k' k², through which it is secured to the grain-box, on the one side by screws and upon the other by a bracket or hanger, L. This hanger is secured in place by screws, and has a socket formed in it at l, for the reception of the tapering lug or flange k² on the casing, the arrangement being such that after 120 the several distributor-casings have been secured in place they can be readily removed and replaced or renewed when required without disturbing the hangers L, the latter serving to determine their position with precision. 125

130 The casing has an arm formed upon it, in which is formed a half-bearing at k³ for the reception of the rock-shaft M, by means of which the gages regulating the discharge of the grain are adjusted, and the bracket or hanger L has also an arm, l', overhanging the shaft M, and provided at l' with a quarter-bearing for said shaft, which forms an extension of the half-bearing k³, and serves to hold the shaft

snugly thereon. By this arrangement of the bearings in the casing and their hangers, united as described, any binding or cramping of the shaft, such as is usually consequent upon the 5 warping, &c., of the grain-box, is avoided.

One part of the divided casing or shell (see Fig. 10) has a funnel-shaped hopper or seed-cup formed in it, and at the side of this, adjacent to the distributing-wheel N, there is a 10 rabbet in the forward wall of the funnel or hopper at K', forming a depressed seat for the flange of the feed-wheel in such manner as to bring the inner face of the flange into the same plane with the front and lower wall of the 15 seed-cup in the shell or casing plate.

The rear wall, K², of the seed-cup projects laterally within the flanged feed-wheel N, and is notched or cut away at n, to form a passage-way for the flange on the wheel.

20 The foot or swinging end of the gage m swings in and out behind the lower end of this wall K², regulating the size of the channel in the feed-wheel, or between the gage and the flange of the wheel, being adjusted by means 25 of an arm, m', made adjustable on the rock-shaft M, by means of which the series of gages can be simultaneously adjusted for controlling the discharge of the grain as desired.

The gages are pivoted at m² in suitable lugs 30 on the casing-plate at points in rear of and above the distributor-wheel shaft, the lower face of the gage acting as the upper wall of the feed-channel, and serving, by its adjustment, to change the size of said channel without 35 materially changing its form, and causing the heel end of the gage, under all adjustments, to "strike" the grain to the capacity of said channel.

The casing-plates are provided at their 40 lower ends on opposite sides with conical spurs or pivots k⁴, upon which the tube-top O (see Fig. 15) is suspended. This top is made in funnel shape, with a large open mouth at its upper end, surrounding the wind-guards of the distributor at their lower ends, and tapering thence down to the size of and fitting at their 45 lower ends within the upper end of the flexible conductor-tubes suspended therefrom in any usual manner. The upper ends of these 50 tube-tops have each a flat spring, p, secured to it, surrounding said end, except in front, where it is recessed or cut away, forming lugs or ears at o', which overhang the pivots k⁴, said spring p being provided near its ends 55 with perforations or eyes p', which fit over the spurs or pivots k⁴, suspending the tube-tops therefrom, and permitting their longitudinal vibration to accommodate the position of the hoes or teeth, whether arranged in single or 60 in double rank.

The ends of the spring extend slightly forward of the eyes p', forming convenient handles, p², for effecting the adjustment of the spring in applying or removing the tube-top O.

C³ represents the grass-seed box or hopper, arranged by preference in front of the

grain-box, and having end pieces in one piece with and forming extensions of the end boards of the grain-box, as shown, though they may 70 be made separate and removable, if desired. By preference, also, I provide the bottom of this grass-seed hopper with a series of force-feed distributors, Q, similar to those on the grain-box, but smaller, and proportioned to the 75 seed to be operated upon, the shaft for operating the distributor-wheels thereof being connected with the wheel a⁵, and receiving motion from the wheel a' through the transmitting-pinion a⁴, in a manner that will be readily understood. Underneath the discharge-outlet to the distributors Q is arranged an angle-board, R, made in V shape inverted, as shown in section in Fig. 4. This board extends transversely of the frame, and is supported upon 80 a pivot, r, upon which it has a slight rocking movement, sufficient to throw its apex either in rear or in advance of the discharge-outlets in the distributors Q, according as it is desired to deposit the grass-seed in front of or behind 85 the holes or teeth. A shouldered spring-pawl, r', serves to hold the angle-board in either position.

S S represent the hoes or teeth, connected alternately, by means of drag-bars S', to two 90 rocking parallel beams, T T', at their lower swinging edges. These beams are pivoted at their upper edges in the side bars of the main frame, and are provided at one end with one or more ratchet disks or segments, t t.

95 U is a weighted dog or double pawl, the long weighted end of which serves as a handle or lever for operating it. Said dog has two teeth or pawls, u u', arranged opposite or nearly opposite each other, as shown, one engaging with teeth on the ratchet disk or segment t, and the other with those of the disk or segment t'. The rocking beams are designed to be adjusted by hand, and when released from the dog U and rocked in such manner as to bring their lower edges together, as shown in Fig. 4, the several drill-teeth will be brought into the same transverse line, in single rank, in which position only the rear beam need be locked by the dog U, as the drag of the hoes 100 upon the forward beam, T', will hold said beam rocked back against the beam T. By rocking the beam T back and the beam T' forward, separating said beams, the teeth will be thrown into a zigzag relation or double rank, in which 105 position only the forward beam, T, need be locked by the dog U against the drag of the hoes connected with it. Separate pawls t² t³ (see Fig. 16) may be employed for locking the beams T T' in the desired position, or they 110 may be used in connection with the weighted dog U, if preferred.

115 The hoes or teeth are connected by chains V with the lifting-roller G, the operation of which has been described above. Parts of the 120 machine not particularly described may be constructed and arranged in any usual or preferred manner.

I am aware that a single perforated spring

has been used on one side of a tube-top in connection with a perforation or hook on the other side of the tube-top for attaching said tube to the casing. This I do not claim.

5 Having now described my invention, I claim—

1. The distributor-casing provided with the flanges through which it is secured to the hopper, in combination with the separate retaining bracket or hanger L, substantially as and for the purpose described.

2. The casing-plate and its retaining bracket or hanger, provided each with partial bearings for the rock-shaft by which the feed-gages are adjusted, substantially as described.

3. The distributor-casing provided with the wind-guards projecting laterally in front and in rear of the discharge-outlet, for the purpose and substantially as shown and described.

20 4. The gears intermediate between the driving and distributor wheel shafts, adapted to be transposed, whereby the speed of the distributor-shaft can be changed without the aid of extra gears, change of centers, or any adjustment of the parts, substantially as described.

5. The lifting-lever, in combination with the gears connecting it with the lifting-roller, whereby a backward thrust of the lever is 30 made to rock the lifting-roller upward and forward, substantially as described.

6. The lifting-roller having an upward and forward movement, in combination with and operated by means of a lever having a backward and downward movement, and serving 35 to rock said lifting-roller past its pivotal center, for adapting it to sustain the lifted hoes without the aid of catch or pawl, as described.

7. The gear-lever provided with the irregular slot or yoke, in combination with the ir-

regular cam for actuating said lever, made adjustable on its shaft for regulating the throw of said lever, substantially as described.

8. The irregular cam actuating the gear-lever connected with the lifting-roller shaft by 45 the clutch-sleeve or trunnion and through-bolt, adapting it to be adjusted relatively to the throw of said shaft, as described.

9. The lifting-roller shaft, in combination with an adjustable actuating-gear for adjusting the position of the lifting-lever relatively to the lifting-roller.

10. The tube-top or funnel, in combination with the flat spring having eyes or perforations at both ends for attaching it to horns or 55 lugs on the distributor-casing, as described.

11. The pivoted angle-board forming the grass-seed distributor, arranged and operating substantially as described, whereby, by a slight rocking movement, it is adapted to deposit the seed either in front or in rear of the drill-teeth, as described.

12. The pivoted angle-board or grass-seed distributor, in combination with the spring pawl or catch for holding said board, as described.

13. The rocking beams for adjusting the drill teeth or hoes, in combination with the toothed disks or segments and retaining-pawl, substantially as described.

14. The weighted double dog or pawl, in combination with the ratchet disks or segments on the rocking beams to which the drag-bars are attached, substantially as described.

In testimony whereof I have hereunto set 75 my hand this 30th day of May, A. D. 1879.

J. S. BOGLE.
